COMMUNICATION SYSTEM

Roy S. Pitkin, Jr., Minneapolis, Minn.

Application January 5, 1940, Serial No. 312,540

11 Claims. (Cl. 179—1)

My invention relates to telephonic intercommunicator equipment and particularly to volume control apparatus therefor.

The type of intercommunicator equipment with which I am concerned is designed primarily for two-way telephonic communication between two points within the premises of a business or industrial firm or the like and may be extended to provide a system including more than two stations. In the usual equipment each station includes a unit known in the trade as a talk-back loudspeaker and which may be and is used interchangeably as a loudspeaker and a microphone. Intercommunicator stations known in the trade as master stations ordinarily each include a common electronic amplifier for amplifying outgoing signals originating in the talk-back unit used as a microphone, for delivery of the amplified signal through a wire line to another station, and amplifying incoming signals originating at another station for delivery at amplified intensity to the talk-back unit used as a loudspeaker. For this sort of operation the amplifier is connected in circuit between the talk-back unit and the line terminals of the station and a switch known in the trade as a talk-listen switch and having two positions known respectively as talk and listen positions is provided for so reversing the circuit connections that the talk-back unit and the line terminals of the station are connected respectively to the input and output of the amplifier for talking and respectively to the output and input of the amplifier for listening.

In the usual master station the amplifier is provided with a manually adjustable gain control and, since the one amplifier amplifies both incoming and outgoing signals, this gain control affects amplification of both incoming and outgoing signals in the same manner and to the same extent. A master station may be and usually is provided with line selector switching means whereby the station may be connected to any desired one of a plurality of lines. Another type of intercommunicator station known as a remote or secondary station includes only a talk-back unit and may or may not include an adjustable signal attenuation device. Intercommunicator systems may be very elaborate but in any event will include at least one master station. The simplest system would include one master station connected through a wire line to a single secondary station.

With the usual type of intercommunicator equipment installed where one station is in a noisy location such as a machine room or the like

and another station is in a relatively quiet location such as a private office or the like considerable difficulty is experienced in communication between the two stations. Due to the amplifier of the amplifier-equipped one of the stations being used for signals in both directions, a setting of the gain control of the amplifier such that a signal from the quiet location to the noisy location will be distinctly heard above the noise at the noisy location will result in both a signal and the incidental noise transmitted from the noisy location to the quiet location being reproduced in the quiet location at an excessive and unpleasant volume level.

15 Manipulation of the volume control of the master station to alleviate the unsatisfactory condition is both undesirable and impractical because, in a two-way conversation, it would require frequent simultaneous manipulation of the talk-listen switch and the volume control necessitating use of both hands and involving a certain amount of mental distraction, and because it would be difficult, in shifting the volume control upwardly and downwardly, to duplicate the most advantageous settings of the volume control in recurring cycles of manipulation thereof.

An object of my invention is to provide volume control apparatus for telephonic intercommunicator equipment to automatically effect different degrees of amplification for respective directions of signal transmission through said equipment.

Another object is to provide, in such equipment, volume limiting means rendered effective and ineffective by placing the talk-listen switch of the equipment in respective ones of the talk and listen positions thereof.

Still another object is to provide automatic volume control means in the amplifier of an intercommunicator station and arrangements whereby said means is maintained respectively effective and ineffective while the talk-listen switch of the station is in respective ones of the talk and listen positions thereof.

Yet another object is to provide such automatic volume control means and arrangements in a master station and cooperating manually adjustable signal attenuating means in a secondary station having communication connections with said master station.

50 A further object is to provide such volume controlling means of simple, light, compact, reliable and inexpensive construction.

These and other objects and advantages of the invention will more fully appear from the following description made in connection with the ac-

companying drawing, wherein like reference characters refer to the same parts throughout the views, and, in which:

Figure 1 is a simplified electrical connection diagram of a typical telephonic intercommunicator system having incorporated therein an embodiment of my invention.

Fig. 2 is a simplified electrical connection diagram of a typical telephonic intercommunicator system having incorporated therein an embodiment of another form of my invention.

Referring to the drawing and particularly to Fig. 1 thereof an embodiment of my invention is shown operatively associated with a typical telephonic intercommunicator system consisting of a master station and two secondary stations. The master station consists of a talk-back loudspeaker unit 10 operable either as a reproducer or a microphone, an electronic amplifier 11 for amplifying either outgoing or incoming telephonic signals, a talk-listen switch 12, and a line selector switch 13. Each of the secondary stations consists of a talk-back loudspeaker unit 14 connected through a communication wire line 15 to the line selector switch 13 of the master station.

The talk-listen switch 12 is a two-position switch the respective positions of which may be designated as talk and listen positions. When in the talk position, the switch 12 connects the talk-back loudspeaker unit to the input of the amplifier 11 and the output of the amplifier 11 to the line selector switch 13. When in the listen position, the switch 12 connects the line selector switch 13 to the input of the amplifier 11 and the output of the amplifier 11 to the talk-back unit 10. While the talk-listen switches of intercommunicator devices may be of various constructions I have shown the switch 12, for purposes of simplicity, as a five pole double throw knife switch, four poles of which represent the talk-listen switch means of the usual intercommunicator device and one pole of which is additional to the usual switch construction and connected in accordance with my invention. The illustrated switch 12 includes a pair of movable contact elements 12a connected to the talk-back unit 10 through electrical conductors 10a and engaged, when the switch 12 is in its lower or talk position with stationary contact elements 12b which are connected through electrical conductors 16 to input terminals 11a of the amplifier 11. When the switch 12 is in its upper or listen position, the movable contact elements 12a are engaged with a pair of stationary contact elements 12c which are connected through electrical conductors 17 to the output terminals 11b of the amplifier 11. The switch 12 also includes a pair of movable electrical contact elements 12d connected through electrical conductors 18 to the line selector switch 13 and engaged, when the switch 12 is in talk position, with stationary contact elements 12e which are connected through electrical conductors 17 to the output terminals 11b of the amplifier 11. When the switch 12 is in listen position the movable contact elements 12d thereof are engaged with stationary electrical contact elements 12f which are connected through electrical conductors 16 to the input terminals 11a of the amplifier 11.

While line selector switching means of intercommunicator devices may take various forms, I have, for purposes of simplicity, shown a line selector switch 13 in the form of a double pole, double throw knife switch having movable con-

tact elements 13a connected through electrical conductors 18 to the talk-listen switch 12 and being shiftable between positions wherein the contact elements 13a are engaged with respective pairs of stationary electrical contact elements 13b connected to the respective communication lines 15. Where only a single secondary station is associated with a master station the line selector switch 13 may, of course, be omitted and the line 15 to the single secondary station may be directly connected to the talk-listen switch in place of the conductors 18.

All of the above described intercommunicator component parts and the electrical connections therebetween are in accordance with conventional practice. Elements and electrical connections added thereto in accordance with my invention are as follows:

The general principle of my invention is to arrange, in connection with equipment such as that described above, means for limiting the gain of the amplifier 11 and so associating the equipment and the gain limiting means with the talk-listen switch that said means will be maintained effective to limit gain while the switch is in a selected one of its respective talk and listen positions and will be maintained substantially ineffective while the switch is in the other of said positions to enable operation of the amplifier at substantially the maximum gain of which it is capable. To accomplish the intended results the gain which is affected as mentioned above need not necessarily be specifically the gain of the amplifier itself but rather would be the overall gain between one and the other of the talk-back unit 10 and the connected one of the lines 15 previously described.

In Fig. 1 I provide means for reducing overall gain in the form of signal attenuation means, and means operating responsive to operation of the talk-listen switch 12 to maintain said attenuation means respectively effective and disabled while the switch 12 is in respective positions thereof. As previously mentioned the talk-listen switch 12 is provided with a fifth pole which is additional to what is ordinarily provided in the structure of conventional talk-listen switch. The additional pole unit of the talk-listen switch 12 consists of a movable contact element 12g shiftable in unison with the previously described contact elements 12a and 12d and engaged respectively with stationary contact elements 12h and 12j when the switch 12 is respectively in its talk and listen positions.

Signal attenuation means 20, which may consist, as shown, of a manually operable rheostat for use as a parasitic shunt load, is connected to the respective previously described electrical conductors 10a through the movable element 12g and a selected one of the stationary elements 12h and 12j of the switch 12 so as to be connected across the talk-back unit 10 when the switch 12 is in one position and be disconnected when the switch 12 is in the other of its positions.

As shown in Fig. 1 the attenuation device 20 is connected at one of its terminals to the switch contact element 12j and the movable switch element 12g is connected to one of the talk-back unit wires 10a. The remaining one of the wires 10a is connected to the remaining terminal of the attenuation device 20. With this arrangement the intercommunicator master station will be free to operate at its maximum degree of overall gain when the talk-listen switch 12 is placed in its talk position for transmission of

outgoing signals by the intercommunicator and will operate at reduced gain when the talk-listen switch 12 is placed in listen position for reception of incoming signals by the master station. Since the attenuation device 20 is manually adjustable the degree of gain maintained for incoming signals may be adjusted as desired by manipulation of the device 20. Preferably the handle for the control element, such as a knob or the like, is situated on the master station for convenient access to the user of the equipment.

Preferably no gain control of any kind other than the above described apparatus is included in the master station but, if desired, any additional conventional gain control could be incorporated in the amplifier if desired. Signal attenuation means is preferably provided with each of the secondary stations 14 for manually controllably, adjustively variable attenuation of signals transmitted in both directions in the associated line 15. This means may take various forms and may consist of a rheostat such as the rheostat 21 bridged across the line 15 or any other suitable variable attenuation device associated with the line 15 and secondary station 14 to produce results generally similar to those of which the rheostat 21 is capable.

The above described apparatus as shown in Fig. 1, with the attenuation means 20 connected to the stationary contact 12₁ of the talk-listen switch 12, is particularly adapted for use where the master station is situated in a relatively quiet location and the secondary station 14 is situated in a very noisy location. Under such conditions the user of the master station would initiate communication by placing the talk-listen switch in talk position and then speaking into the talk-back unit 10. With the switch 12 in talk position the master station operates at maximum overall gain to produce, in the secondary station talk-back unit, a signal of high intensity so that the same will be heard above the din in the noisy location even if the person called may not be particularly close to the secondary station talk-back unit 14. When the person called approaches his talk-back unit 14 to answer the master station he may set his attenuation device 21 to obtain any percent of the available signal energy he may require for reception of the signal from the master station above the noise. When the user of the master station shifts the talk-listen switch to its listen position for reception of a response from the secondary station the overall gain of the master station will be considerably reduced relative to the high gain employed in my apparatus for outgoing signals to the secondary station so that incoming signals from the secondary will be reproduced at the master station with a low enough intensity to be comfortably listened to in the quiet location of the master station.

The intensity at which incoming signals are reproduced at the master station may, of course, be adjusted by manipulation of the master station attenuation device 20 to suit the user, and such adjustment will in no way affect the strength of signals transmitted from the master station to the secondary station and need be made only once. It should be apparent that the talk-listen switch may be shifted between its talk and listen positions repeatedly during a two-way conversation without any co-incidental manipulation of any gain control and with the master station and secondary station reproducing signals received thereat at widely different re-

spective intensity levels each of which may be controlled by the corresponding one of the participants in the conversation. A certain amount of noise will be transmitted from the secondary station to the master station along with the voice of the person at the secondary station but the person at the master station may control the total combined voice and noise volume and the person at the secondary station may speak close to his talk-back unit to obtain a favorable voice to noise ratio. Thus very satisfactory two-way conversation between respective very quiet and very noisy locations may be carried on over intercommunicator equipment arranged in accordance with my invention with no more manipulation of controls than is required in two-way communication between two quiet locations by means of conventional intercommunicator equipment.

20 The incorporation of an embodiment of my invention in intercommunicator equipment in the manner illustrated in Fig. 1 may be effected at very little expense and provides equipment particularly well adapted for use where economy is an important factor, where only one secondary station is required, or where several secondary stations associated with the master station are situated in substantially equally noisy locations. The equipment of Fig. 1 is entirely feasible for 30 use with secondary stations in respective quiet and noisy locations and such use merely necessitates that the attenuation means 20 be set in different positions when communicating with stations affected by different amounts of noise.

35 In Fig. 2 I have illustrated the same intercommunicator equipment as that of Fig. 1 but have also shown therein an embodiment of my invention wherein the need for adjusting any control when the master station successively receives incoming signals from secondary stations in respectively quiet and noisy locations is obviated. In the device of Fig. 2 I show, as in Fig. 1, means for limiting the overall gain of the master station and I so associate the components of said 40 gain limiting means and said master station with the talk-listen switch that said means will be maintained effective to limit overall gain of the master station while said switch is in one of its respective talk and listen positions and will be 45 maintained substantially ineffective while the switch is in the other of said positions to enable operation of the master station at substantially the maximum gain of which it is capable.

50 In Fig. 2 I provide electronic automatic volume 55 control apparatus operative responsive to signal intensity to vary the gain of the amplifier 11 in generally inverse ratio to the signal intensity and so associate said apparatus with the components of said master station as to effect maintenance of said apparatus effective and substantially ineffective for volume limiting action while the talk-listen switch is in respective ones of its talk and listen positions.

The system of Fig. 2 is identical with that of 60 Fig. 1 with the exception that the attenuation device 20 is omitted and certain other elements to be described are substituted therefor. All of the elements appearing in both Fig. 1 and Fig. 2 are identified by the same reference numerals in both figures. For reasons which will be apparent certain details of the amplifier 11 which do not appear in Fig. 1 are shown in Fig. 2 and will be described.

65 In the amplifier 11 an input transformer 22 is provided having a primary winding 22_p connected

to the amplifier input terminals $11a$ and a secondary winding one end of which is connected to the grid $23g$ of an amplifier tube 23 . The cathode $23c$ of the tube 23 is connected through a self-biasing resistor 24 to the chassis $11c$ of the amplifier 11 . An output transformer 25 is provided having a secondary winding $25s$ connected to the output terminals $11b$ of the amplifier 11 and a primary winding $25p$ one end of which is connected through a wire 26 to the plate $27p$ of an output tube 27 provided in the amplifier 11 .

I provide electronic automatic volume control apparatus for converting signal voltage into an amplifier gain controlling direct current voltage usually referred to as an automatic volume control voltage and customarily referred to in the trade in an abbreviated manner as an a. v. c. voltage. While the automatic volume control apparatus may take various forms we have illustrated a suitable form at 28 having a signal input wire $28a$ and an a. v. c. voltage output wire $28b$. A diode vacuum tube 29 is provided and its plate $29p$ is connected through a signal coupling and direct current blocking condenser 30 to the input wire $28a$. The cathode $29c$ of the diode 29 is connected to the chassis $11c$ of the amplifier 11 . The plate $29p$ of the diode 29 is connected through two resistors 31 and 32 to the a. v. c. voltage output wire $28b$. A sensitivity control for the a. v. c. apparatus 28 is provided in the form of a rheostat 33 connected between the junction between the resistors 31 and 32 and the chassis $11c$. A condenser 34 is connected between the output wire $28b$ and the chassis $11c$. The wire $28b$ is connected to the previously unmentioned end of the secondary winding $22s$ of the input transformer 22 through a resistor 35 and said end of the winding $22s$ is connected to the cathode $23c$ of the amplifier tube 23 through a condenser 36 . The resistors 31 , 32 , and 35 and the condensers 34 and 36 constitute a filter such as is ordinarily included in automatic volume control apparatus and are of such values that the filter will enable production of an a. v. c. voltage proportional to the average amplitude of the audio frequency wave of the signal voltage applied to the a. v. c. apparatus rather than an a. v. c. voltage which fluctuates in proportion to said amplitude. The signal input wire $28a$ of the a. v. c. apparatus may be connected to any point in the amplifier whereat a signal voltage exists but is preferably connected to the wire 26 and thereby to the plate $27p$ of the output tube 27 .

As will be readily understood from the well known principles of a. v. c. circuits the positive half wave of the signal voltage on the plate $29p$ of the a. v. c. tube 29 will be short circuited to the chassis $11c$ through the a. v. c. tube 29 and the negative half wave will be free to develop an a. v. c. voltage on the wire $28b$ of negative polarity relative to the chassis $11c$. From the previously described circuit of Fig. 2 it should be apparent that the a. v. c. voltage appears as a negative bias on the grid $23g$ of the amplifier tube 23 additional to the bias produced in the self-biasing resistor 24 and that increase in signal voltage at the plate $29p$ of the a. v. c. tube 29 will increase this bias to decrease amplification in the amplifier tube 23 so as to limit the amplifier signal intensity and tend to maintain a substantially constant signal intensity at the output terminals $11b$ of the amplifier 11 even though the signal input at the input terminals $11a$ may vary. The setting of the rheostat 33 will determine the intensity level to be automatically maintained by the a. v. c. ap-

paratus and the control element, such as a knob or the like, for the rheostat 33 should be situated on the master station for convenient access thereto by a user of the master station.

5 Means operating responsive to operation of the talk-listen switch 12 is provided for maintaining the a. v. c. apparatus 28 respectively operative and substantially ineffective for limiting amplifier gain while the switch 12 is in one and the other 10 of the listen and talk positions thereof. While this may be accomplished in various ways, I have included the additional switch elements $12g$, $12h$ and $12j$ for this purpose. A wire 37 is connected between the a. v. c. voltage output wire $28b$ and the movable switch contact element $12g$ and a wire 38 is connected between the chassis $11c$ and the stationary switch contact $12h$.

It should be apparent that the a. v. c. apparatus is operative to control the gain of the amplifier 11 while the talk-listen switch 12 is in listen position but that the a. v. c. voltage will be short circuited by the switch contacts $12g$ and $12h$ while the switch 12 is in talk position so that the amplifier 11 will then operate at the maximum gain of which it is capable. It should be apparent that the wire 37 , instead of being connected to the wire $28b$, could just as well be connected to any one of several other points such as the lower end of the input transformer secondary winding $22s$, the junction between the resistors 31 and 32 or the plate $29p$ of the diode a. v. c. tube 29 .

Use of the equipment of Fig. 2 by the user thereof is effected in exactly the manner previously described in connection with use of the equipment of Fig. 1 except that no manipulation of the knob of the sensitivity control 33 is necessary when the master station is used for communicating successively with secondary stations in respectively quiet and noisy locations whereas, in use of the equipment of Fig. 1 under the same conditions, manipulation of the attenuation device 20 would be necessary.

If it is desired that the a. v. c. apparatus 28 be effective on outgoing signals and ineffective on incoming signals rather than as described above the wire 38 may be connected to the switch contact $12j$ instead of to the switch contact $12h$. This connection could be used in cases where the master station is in a noisy location and the secondary station is in a quiet location.

It is believed obvious that embodiments of my invention may be readily used in any type of telephonic intercommunicator equipment having a common electronic amplifier for signals in both of opposite directions even though the master station may have separate microphone and reproducer units in place of a talk-back unit or even though the communication circuit between stations may be of the carrier current type as used in the so-called wireless intercommunicators instead of being in the form of an ordinary audio frequency wire circuit or line.

Commercial intercommunicator equipment having embodiments of my invention incorporated therein have been placed in regular service and have enabled highly satisfactory communication service in locations where noise conditions have rendered conventional intercommunicator equipments extremely unsatisfactory and practically useless for their intended purpose.

It is apparent that I have invented novel, effective, simple and inexpensive automatic volume control apparatus for telephonic intercommunicator equipment capable of providing highly

satisfactory communication between station locations subjected to widely different noise intensities.

In the claims, the terms, "intercommunicator station" and "talk-listen switch" are to be construed as meaning the types of apparatus described in such terms in the preamble of this application and the terms "talk position" and "listen position" are to be interpreted in accordance with the explanation thereof in the preamble.

It will, of course, be understood that various changes may be made in the form, details, arrangement and proportions of the various parts without departing from the scope of my invention.

I claim:

1. The combination with a two-way telephonic intercommunicator station including a combined microphone and reproducer means, a common electronic amplifier for both outgoing and incoming signals and a talk-listen switch, of means associated with said station for imposing a limit on the intensity of signals handled thereby below the maximum signal handling capability of said station, and means operating responsive to operation of said switch for maintaining said limiting means in substantially ineffective condition while said switch is set in only one of the respective talk and listen positions thereof whereby the full signal handling ability of said station will be available only when said switch is in said one position.

2. The combination with a two-way telephonic intercommunicator station including microphone and reproducer means, a common electronic amplifier for both outgoing and incoming signals and a talk-listen switch, of attenuation apparatus effecting only signals transmitted in one direction and comprising means associated with said station for attenuating signals passing therethrough, and means associated with and operating responsive to operation of said switch for maintaining said attenuation means operative or substantially inoperative while said switch is in respectively one or the other of the talk and listen positions thereof.

3. The combination with a two-way telephonic intercommunicator station including a unit interchangeably useable as a microphone and a reproducer, a common electronic amplifier for both outgoing and incoming signals and a talk-listen switch, of signal attenuation means effecting only signals transmitted in one direction and comprising manually variable attenuation means connected to said unit to reduce signal energy thereat, and electrical contact means incorporated in said switch to maintain said attenuation means ineffective only while said switch is in one of the talk and listen positions thereof.

4. The combination with a two-way telephonic intercommunicator station including microphone and reproducer means, a common electronic amplifier for both outgoing and incoming signals and talk-listen switch, of automatic volume controlling means effective only on signals transmitted in one direction and comprising automatic volume control apparatus working responsive to signal voltage at a selected point in said station to vary the gain of said amplifier in generally inverse relation to the magnitude of said signal voltage, and means associated with and operating responsive to operation of said switch for maintaining said automatic volume control apparatus in substantially disabled condition

only while said switch is in one of the talk and listen positions thereof whereby the full gain of said amplifier will be available only while said switch is in said one position.

5. The combination with a two-way telephonic intercommunicator station including microphone and reproducer means, a common electronic amplifier for both outgoing and incoming signals and a talk-listen switch, of automatic volume controlling means effective only on signals transmitted in one direction and comprising automatic volume control apparatus working responsive to signal voltage at a point in said station to vary the gain of said amplifier in generally inverse relation to the magnitude of said signal voltage, manually controllable means for adjustively varying the degree of response to said automatic volume control apparatus to said signal voltage, and means associated with and operating in unison with said switch for maintaining said automatic volume control apparatus in ineffective condition only while said switch is in one of the respective talk and listen positions thereof.

25 6. The combination with a two-way telephonic intercommunicator station including microphone and reproducer means, a common electronic amplifier for both outgoing and incoming signals, and a talk-listen switch, of automatic volume controlling means effective only on signals transmitted in one direction and comprising automatic volume control apparatus working responsive to signal voltage at a point in said station to provide a direct current automatic volume control voltage applied to said amplifier to vary the gain thereof in generally inverse relation to said signal voltage, and electrical contacts provided in said switch for maintaining a short circuit of a portion of said apparatus only while said switch is in one of the talk and listen positions.

35 7. The combination with a two-way telephonic intercommunicator station including microphone and reproducer means, a common electronic amplifier for both outgoing and incoming signals, and a talk-listen switch, of automatic volume controlling means effective only on signals transmitted in one direction and comprising automatic volume control apparatus working responsive to signal voltage at a point in said station to provide a direct current automatic volume control voltage applied to said amplifier to vary the gain thereof in generally inverse relation to said signal voltage, and electrical contacts provided in said switch for maintaining a short circuit of said automatic volume control voltage only while said switch is in one of the talk and listen positions thereof.

45 8. The combination with a two-way telephonic intercommunicator station including microphone and reproducer means, a common electronic amplifier for both incoming and outgoing signals, and a talk-listen switch, of automatic volume control apparatus operable responsive to a signal voltage applied thereto to vary the gain of said amplifier in generally inverse relation with variation in the applied signal voltage, said apparatus being connected to said station at a point therein where a signal voltage exists at respectively unamplified and amplified magnitudes while said switch is in respective ones of the talk and listen positions thereof.

50 9. The combination with a two-way telephonic intercommunicator station including a unit interchangeably operable as a microphone and a

reproducer and having a pair of terminals, a common electronic amplifier for both incoming and outgoing signals, a pair of terminals for connection to a line, and a talk-listen switch, of automatic volume controlling means effective only on signals transmitted in one direction and comprising automatic volume control apparatus operative responsive to a signal voltage applied thereto to vary the gain of said amplifier in generally inverse relation to variation of said voltage, and electrical connections for effecting application to said apparatus of signal voltage at one of said pairs of terminals whereby negligible and amplified signal voltages will be respectively applied to said apparatus while said switch is in respective ones of the talk and listen positions thereof.

10. The combination with a two-way telephonic intercommunicator station including a unit interchangeably operable as a microphone and a reproducer, a common electronic amplifier for both incoming and outgoing signals, and a talk-listen switch, of automatic volume controlling means effective only on incoming signals transmitted in one direction and comprising automatic volume control apparatus operative responsive to a signal voltage applied thereto to provide a di-

rect current automatic volume control voltage applied to said amplifier to vary the gain thereof in generally inverse relation to variation in the signal voltage applied to said apparatus, and electrical connections communicating the signal voltage at said unit to said apparatus whereby negligible and amplified signal voltages will be respectively applied to said apparatus while said switch is respectively in talk and listen positions thereof.

11. The combination with a two-way telephonic master station including microphone and reproducer means, a common electronic amplifier for both outgoing and incoming signals, and a talk-listen switch, a two-way telephonic secondary station including microphone and reproducer means, and a line interconnecting said stations, of volume controlling means comprising volume limiting means associated with said master station to affect signals handled thereby and to be maintained effective only while said switch is in a predetermined one of its respective talk and listen positions, and adjustively variable signal attenuating means at said secondary station associated therewith for attenuation of both incoming and outgoing signals.

ROY S. PITKIN, JR.
